INVENTOR

UNITED STATES PATENT OFFICE.

CARLETON ELLIS, OF NEW YORK, N. Y., ASSIGNOR TO COMBUSTION UTILITIES COMPANY, OF NEW YORK, N. Y., A CORPORATION OF NEW YORK.

GAS-PRODUCER.

No. 811,208.

Specification of Letters Patent.

Patented Jan. 30, 1906.

Application filed March 15, 1905. Serial No. 250,178.

To all whom it may concern:

Be it known that I, CARLETON ELLIS, a citizen of the United States, and a resident of New York city, in the county of New York and State of New York, have invented certain new and useful Improvements in Dry-Seal Gas-Producers, of which the following is a specification.

My invention relates to improvements in gas-producers in which the water seal for the collection and removal of ash is dispensed with; and the objects of my improvement are, first, to provide a means for the easy removal of the dry ash and clinker from the lower part of the producer; second, to secure an even distribution of the blast-gases throughout the mass of gas-producing fuel; third, to do away with water and moisture in the lower part of the producer in order to reduce as far as possible the amount of hydrogen contained in the producer-gas. I attain these objects by the apparatus illustrated in the accompanying drawings, in which—

Figure 1 is a vertical section of the apparatus; Fig. 2, an elevation in which the lower part of the producer is shown in section along the line A A of Fig. 1.

Similar figures refer to similar parts in the two views.

Referring to Fig. 1, 1 is a shell having the lining 2, of fire-brick or other refractory material. 3 is an outlet for the combustible gas. 4 is a feed-hopper provided with the lid 5 and coal-spreading device 6. The lower part of the lining 2 increases in thickness near the base and forms the shoulder 7. Extending midway or diametrically across the producer and spanning the ash-pit is the deflecting or blast baffle 8, which has, as shown in Fig. 2, deflecting or sloping sides. The baffle 8 is supported by the support 9, which divides the ash-pit 10 into two chambers. Outlet-passages 11 in the lower part of this divided ash-pit are provided with screw conveyers 12 12, which may be actuated by the wheels 13 13. The ash-pit is provided with poking-holes 14 14 for breaking up clinker aggregations. Poking-holes are also provided at 15. The disposition of twyers or blast-inlets is shown at 16.

My method of operation is as follows: A fire is started in the producer and coal is fed in through the hoppers 4 4 until a deep bed of ignited coal is obtained. When in a suitable state of ignition for the production of gas, an

air-blast is directed through the twyers 16 16, 55 striking against the blast-baffle 8. The blast is deflected upward and passes uniformly through the mass of fuel. By the time the gases have reached the upper level they will be found converted into combustible gas 60 which may be removed through the pipe 3 and carried to the place of consumption. The ash which forms in the lower part of the producer collects in the ash-pit 10. This ash may be removed from time to time by operating the 65 screw conveyers 12 12. In case the ashes form a bridge or arch in the ash-pit and refuse to fall into the conveyers a bar may be inserted at 14 to break up such formation.

I do not limit myself to the exact form of 70 construction herein described. For instance, I do not wish to restrict myself to the use of only two conveyers nor to their particular form of construction. The blast-baffle for deflecting the gas need not have smoothly- 75 inclined sides, but may have a step-up form— such, for instance, as would be produced by laying fire-brick in step-like fashion. The cooling medium which ordinarily must be supplied in the air-blast to prevent the formation 80 of objectionable clinker or slag in the producer may be either carbon dioxid or steam. I prefer, however, to use products of combustion, such as may be obtained from furnaces, steam-boilers, lime or cement kilns, 85 glass-furnaces, or other operations producing carbon dioxid as a waste product in large quantities. The combustion portion of the gas produced by such a method is largely carbon monoxid, together with some methane 90 and other products of destructive distillation of the fuel, and, moreover, contains little or no hydrogen. It is therefore particularly adapted for use in the operation of internal-explosion engines. 95

What I claim as my invention, and desire to secure by Letters Patent, is—

1. In a dry-sealed gas-producer, the combination of a shell with closed lower end forming an ash-chamber, a screw conveyer 100 for removing ash from the chamber, a baffle-wall spanning the shell above the chamber, and blast-twyers piercing the sides of the shell and directed against the baffle-wall.

2. In a dry-sealed gas-producer, the combination of a shell with closed lower end forming an ash-chamber, a screw conveyer 105 for removing ash from the chamber, an up-

wardly-tapering baffle-wall spanning the shell above the chamber, and blast-twyers piercing the sides of the shell and directed against the baffle-wall.

- 5 3. In a dry-sealed gas-producer, the combination of a shell with a closed lower end forming an ash-chamber, a partition across the chamber, subdividing it into compartments, a screw conveyer for removing the ash 10 in each compartment, an upwardly-tapering baffle-wall spanning the shell above the partition and supported thereby, and blast-twyers piercing the sides of the shell and directed against the baffle-wall.
- 15 4. In a dry-sealed gas-producer, the combination of a shell with a closed lower end

forming an ash-chamber, a partition across the chamber, subdividing it into compartments, a screw conveyer for removing the ash in each compartment, an upwardly-tapering baffle-wall spanning the shell above the partition and placed at an angle thereto, and blast-twyers piercing the sides of the shell and directed against the baffle-wall. 20

Signed at New York city, in the county of 25 New York and State of New York, this 13th day of March, A. D. 1905.

CARLETON ELLIS.
